W. B. Hutchinson,
ATTORNEY

UNITED STATES PATENT OFFICE.

AARON S. NICHOLS, OF NEW YORK, N. Y.

SPRAYING APPARATUS.

1,361,607.

Specification of Letters Patent.

Patented Dec. 7, 1920.

Application filed March 25, 1919. Serial No. 285,127.

To all whom it may concern:

Be it known that I, AARON S. NICHOLS, a citizen of the United States, and a resident of the city, county, and State of New York, 5 have invented a new and useful Improvement in Spraying Apparatus, of which the following is a full, clear, and exact description.

My invention relates to improvements in apparatus designed to throw liquid into a spray, and is more especially designed for apparatus of this kind in which a substantial volume of spray is desired. An important use of apparatus such as described is in connection with air washing devices, but the spraying device can be used for other purposes. My improvements apply to machines or apparatus of the general character disclosed in Letters Patent of the United States 20 No. 1,296,315, dated March 4th, 1918, for improvements in air washing apparatus. In apparatus of this kind rotary disks are used which dip slightly into the liquid to be sprayed, and then pick up and break up the 25 liquid into a spray. Heretofore it has been the practice in such apparatus to have parallel disks mounted on a shaft and arranged at right angles to the shaft so as to dip into the water or liquid to be sprayed. I have 30 found by experiments, however, that if the disks are pitched at an inclination to the shaft, I get a much better effect, as in this case the spray picked up by a particular disk is thrown violently against the adjacent disk and is thus broken up into very 35 fine particles. Even though the edges of the disks may be constructed to pick up and break up the liquid, I still get an appreciably better effect if the disks are inclined, 40 for the reasons stated above. In carrying out this idea I have had the best results by arranging the disks at an inclination to the shaft, and in substantially parallel relation, but they can be arranged at opposite inclinations, 45 and at various inclinations with respect to each other, without affecting the invention. The disks also can be secured to their shaft in any convenient way, and I have shown a suitable means of attachment.

50 Reference is to be had to the accompanying drawings forming a part of this specification, in which similar reference characters indicate corresponding parts in all the views.

Figure 1 is a sectional elevation showing 55 the general arrangement of disks, disk chamber, and liquid.

Fig. 2 is an enlarged sectional view showing a convenient means of fastening the disks to their shaft, the middle portions of the disks only being shown. 60

Fig. 3 is a side or edge view of a washer which can be used to give the disks the desired pitch.

Fig. 4 is a cross section of the washer.

Fig. 5 is an end view of a part of the 65 collar which carries one of the disks, and

Fig. 6 is a view similar to Fig. 2 but showing a modified arrangement of the disks.

Apparatus of this kind is generally arranged with a shaft 10 turning in a chamber or box 11 above a body of liquid 13 which is sometimes heated by pipes 14, but whether or not the liquid is heated has nothing to do with this invention. The disks 12 are generally formed with peculiarly 70 constructed edges, as for instance in the patent hereinabove cited, so as to pick up the water readily, but my invention has no reference to the conformation of the edges, but rather to the arrangement and pitch of 75 the disks by which I get a new and better result. As shown in Fig. 2 the disks are preferably substantially parallel but at an inclination to the shaft 10. My invention does not lie in the manner in which the 80 disks are attached to their shaft, but I have shown a convenient means so as to make it clear that the invention can be carried into effect. As illustrated each disk is mounted on a collar 13¹ which is attached to the 90 shaft 12, and this collar has a tapering hub 14 which is slit at intervals longitudinally as at 15 (see Fig. 3) so as to make spring segments. The disk fits on the hub and against one side of the collar 13 and a tapering nut 16 screws on the part 14 of the collar and thus fastens the disk in place, and at the same time clamps the segments of the 95 collar to the shaft.

In order that the disks may be given the 100 right pitch, washers 17 may be used which are thick on one edge and thin on the opposite edge, and these may be placed in opposite relation as shown in Fig. 3, and slipped on over the hub of the collar 13 so 105 as to clasp a disk 12 between them, and thus the latter will be given an inclination with respect to the shaft 10. As stated above other means can be adopted for fastening the disk.

110 In Fig. 6 I have shown a disk arranged out of parallel but still inclined with re-

spect to the shaft 10, so as to get the effect desired, that is to say, when the disks are inclined they not only appear to pick up the water better and break it up into fine 5 particles, but they also throw it laterally against the adjacent disk and make the spray still finer.

In Figs. 2 and 3 for the sake of clearness only the middle portions of the disks are 10 shown, but it will be seen that if they were carried out to their full diameter the edges would be nearly together, and it will be readily understood how the above action takes place.

15 Where the wedge shaped washers 17 are used, it is advisable to have the flange of the collar 13¹ provided with pins 18 which extend through corresponding holes 19 in the washers and in the disks 12, and this 20 prevents the washers from slipping around so as to get the thick sides opposite each other.

Attention is called to the fact that in order to have the apparatus work successfully 25 there must be at least a plurality of disks. This apparatus is used when it is necessary to produce a very fine spray, which is practically a mist, in order that air may be washed and the nicer operations of removing 30 dirt and impurities perfectly carried

out. If a single disk were used it would not have the desired result, but when a plurality are used, and they are placed at an inclination to their axis and arranged side by side, it will be seen that the jets and particles 35 of water which are picked up by one disk impinge against the next disk, and are thereby broken up, and furthermore the particles raised by the several disks impinge against each other, and the result is an exceedingly fine spray. This apparatus has been tried out successfully in practical use, and results in a much finer spray than has heretofore been produced.

I claim:—

1. A spraying apparatus comprising a shaft, and a series of rotatable disks mounted on the shaft and adapted to dip into a body of liquid, said disks being held at an inclination to the shaft.

2. A spraying apparatus comprising a rotatable shaft, and a series of disks secured to the shaft and adapted to dip into a body of liquid, said disks being inclined with relation to the shaft and arranged at different 55 inclinations.

AARON S. NICHOLS.
